ATTORNEY

UNITED STATES PATENT OFFICE.

MANUEL PRIETO, OF MEXICO, MEXICO.

CAR-COUPING.

SPECIFICATION forming part of Letters Patent No. 600,209, dated March 8, 1898.

Application filed March 6, 1897. Serial No. 626,306. (No model.)

To all whom it may concern:

Be it known that I, MANUEL PRIETO, of the city of Mexico, in the Republic of Mexico, a citizen of said Republic, temporarily residing 5 in the city of New York, in the State of New York, have invented a certain new and useful Improvement in Railroad-Car Couplings, of which the following is a specification.

My improvement may be applied to couplings for cars of all sizes and classes for use on all kinds of railroads. I will describe it mainly as applied to a coupling for freight-cars on ordinary railways.

I provide for easily opening the coupling 15 by the operator either on the platform or at the top of the car. The parts instantly adjust themselves, so that the coupling will engage promptly with an ordinary coupling-link when it is thrust in by the movement of 20 one of the cars. The parts may operate by gravity alone.

The accompanying drawings form a part of this specification and represent what I consider the best means of carrying out the invention.

Figure 1 is a side elevation, a portion of the coupling being broken away to economize space on the drawing. Fig. 2 is a corresponding elevation with certain parts removed and 30 is partly a central longitudinal vertical section with the link engaged. Fig. 3 is a front view corresponding to Figs. 1 and 2. Fig. 4 is a central longitudinal vertical section corresponding to Fig. 2, but with the coupling 35 open. It is shown in the act of receiving the link from another car, which will liberate the trigger and effect the coupling. Fig. 5 is a horizontal section of the pin detached and showing its offset having the vertical grooves 40 into which extend the pins rigidly attached to the cover to guide the vertical movements of the coupling-pin. The remaining figures show details detached. Fig. 6 is a side view, and Fig. 7 a plan view, of the internal lever. Fig. 8 is a side view, and Fig. 9 an edge view, of the connecting-piece or toggle. Fig. 10 is a side view, and Fig. 11 an edge view, of what I denominate the "trigger." Fig. 12 is an elevation of a piece which is secured on 45 the end of the car to support the operating-rod. Fig. 13 is a plan view showing a modi-

fication of a portion. Fig. 14 shows the details of the connections for setting the pin by the treadle illustrated in Fig. 13. Fig. 15 is a fragmentary view illustrating in plan the 55 manner in which the securing-bolt engages the end of the coupling-neck.

Similar letters of reference indicate corresponding parts in all the figures where they appear.

A is the body or coupling-head, of cast-iron or other suitable material. It may be mounted on the car in any ordinary or suitable manner, under the end of the car, (not shown,) with liberty to swing laterally and to yield 60 somewhat longitudinally, as will be readily understood. Certain portions will be designated, when necessary, by supernumerals.

A' is a removable cover which allows access to the simple internal parts when required for 65 examination or repairs. The flaring throat a may be of the ordinary form and dimensions, adapted to receive a coupling-link M from another car.

B is a stout vertical pin provided with a 70 transverse pin B' near its upper end, by which it may be raised and lowered to the extent required. When it is down, its lower end is received in a sufficient pocket a' in the base 75 of the aperture a.

D is a horizontal shaft supported in bearings in the head A and having fixed on its outer end an arm D', to which force may be applied, as will be described farther on, to effect the opening of the coupling.

E is a lever adapted to turn in a space a² in the upper portion of the head. It is fixed on the shaft D, so as to turn therewith, and performs important functions. Its front end is forked, as indicated in Fig. 7, and engages 80 the transverse pin B' in the slots e. Its opposite end is deep and provided with a slot e', which receives a pin G', set in the toggle-piece G, the slot allowing considerable movement of one part before motion will be necessarily imparted to the other. The lower side of the lever E near the mid-length is provided with a deep recess e² and near it is a shallow and rounded recess e³, which latter receives the nose of the trigger when the coupling is 85 set in the open position.

H is the trigger, certain portions being des-

ignated, when necessary, by supernumerals. It turns loosely on a transverse pin A², set in the head.

H' is a nose which when the coupling is engaged lies idly in the deep recess e² and when the coupling is set engages in the shallow recess e³ and holds the pin B in its elevated position. A smoothly-rounded surface H³ is adapted to receive the impact of the link M, which is thrust into the flared mouth a from another car. The back face of the lower end of the trigger is formed as a stout knuckle H³, which engages by a pin I with the lower end of the toggle G.

15 The upper end of the coupling-pin B is extended rearward to present an offset, as indicated by B², which is formed at the sides to present vertical guide-grooves b, which receive corresponding straight smooth pins A³, 20 extending downward from the lower face of the cover A'. These serve to guide the pin as it is moved up and down by the tilting of the lever E.

The rear end of the shank or neck of the 25 head is somewhat enlarged, as indicated by A⁴ in Figs. 1, 2, and 15, and has a T-shaped slot vertically, into which the head O of the securing-bolt engages.

30 The arm D' extends in an approximately horizontal position, but inclined upward or downward, according as the coupling is open or closed. To effect the opening of the coupling, I depress the arm D' forcibly by the aid of a cross-lever K, which is pivoted between 35 lugs A⁵ A⁶, cast on the side of the coupling-head A, and extends outward to a sufficient distance to give a very effective leverage. The operator may apply his strength directly to that lever K, or if he is up at the top of the 40 car he operates through a rod L, extending upward, as shown.

The upper end of the rod may be formed with a handle L', by which the lever K is operated. The operation of setting the pin 45 simply requires the lever K to be depressed, and said pin will be elevated and secured by the engagement of the nose H' of the trigger H in the notch e³. The dropping of the pin will allow the restoration of the lever K by 50 the attendant. It may be held suspended by the aid of a spring P, which is mounted in the housing F, secured on the end of the car, the rod L being engaged therewith by means of a side arm L², which is thrust into the housing 55 F above the spring.

I attach importance to the support and guidance of the coupling-pin independently of the loosely-connected lever, because it relieves the latter from any strain except that 60 required to overcome the gravity of the lever and pin and the slight friction involved. The lever E may be light and lightly mounted.

I attach importance to the toggle or link G, because, although slotted, so as to be loose, its 65 looseness has a limit, and it insures that when the lever E is manually operated the trigger shall drop into position for holding the coup-

ling open if friction or other slight cause might prevent the gravity of the trigger from attaining this end.

Modifications may be made without departing from the principle or sacrificing the advantages of the invention. The housing F may be made longer and the spring P correspondingly lengthened, so that the lever K 75 may be depressed to the full extent required to elevate the coupling-pin and disengage the coupling without taking the arm L² out of its engagement with the spring, but simply depressing the spring by the strength of the 80 operator. It will be preferable in most cases to disengage the arm L² from its place over the spring P by a lateral movement of the rod L, as above described. The form of the coupling-head may be varied within wide 85 limits.

In Figs. 13 and 14 I have illustrated an arrangement for actuating the lever E by the foot of the attendant. The treadle R, preferably weighted, is pivotally mounted at any 90 suitable point and is connected by a short link R' with an arm secured in the end of the shaft D. This allows the foot to be applied with the proper leverage without extending into contact with the transverse timber of the 95 car.

I claim as my invention—

1. In a car-coupling, the head having the link-opening and the vertically-movable pin, in combination with the manually-elevated horizontal lever E, and trigger-block H for engaging and sustaining the same, and both pivoted in the upper part of the head, the lever being in slotted engagement at its front with the pin, and engaged by a toggle connection at its rear with said block, said pin, lever, toggle and block being inclosed and supported within the head, substantially as herein specified.

2. In a car-coupling, the head having the link-opening and the vertically-movable pin and lever E in slotted engagement therewith, said lever being positively secured on a shaft D, free to turn in bearings in the head and rigidly carrying an arm at a right angle, and the transverse manually-operated lever K, independent of the arm D' but arranged to depress the same, in combination with a trigger-block loosely connected with the lever E, and arranged to sustain it and be struck by the entering link, substantially as herein specified.

3. In a car-coupling, the head containing the vertically-movable pin B and manually-operated lever E loosely engaged therewith and having the under recess e² and shallower recess e³, in combination with means for turning such lever to raise the coupling-pin at will, and with the trigger-block H having a nose H' for engaging the recess e³ to support the lever and arranged to be struck by the link M to liberate the parts and effect the coupling, substantially as herein specified.

4. In a car-coupling, the head having the

link-opening and the vertically-movable pin, in combination with the manually-elevated horizontal lever E, and trigger-block H, for engaging and sustaining the same, and both 5 pivoted in the upper part of the head, said block having a rear knuckle loosely connected by a toggle with the rear end of the lever, the front end of which is in slotted engagement with the pin G', substantially as herein 10 specified.

5. In a car-coupling, the head containing the vertically-movable pin B and pivoted lever E, in slotted engagement therewith, and having a rear toggle connection with a pivoted trigger-block H for engaging the lever and holding it and the pin elevated, in combination with lever-operating means including the rod L having the projection L² for 15

engaging a spring P in a housing F, substantially as herein specified. 20

6. In a car-coupling, the head containing the vertically-movable pin having the rear offset B², with a vertical groove b a removable cover having a guide-pin A³ depending into said recess, a pivoted lever E, in slotted engagement at its front with the pin B and connected with a trigger-block H for holding it and the pin elevated and located to be struck by the link, substantially as herein specified. 25

In testimony that I claim the invention above set forth I affix my signature in presence of two witnesses. 30

MANUEL PRIETO.
